DISPLAY STAND

Stanley Joseloff, Westport, Conn.

Application December 3, 1954, Serial No. 33,388

Term of patent 14 years

(Cl. D80—9)

The broken lines are shown for illustrative purposes only.

I claim:

The ornamental design for a display stand, as shown and described.
